UNITED STATES PATENT OFFICE.

JONES T. TEMPLETON, OF ST. LOUIS, MISSOURI, ASSIGNOR TO THE BUCK'S STOVE & RANGE COMPANY, OF ST. LOUIS, MISSOURI, A CORPORATION OF MISSOURI.

DESIGN FOR A HEATING STOVE.

Application filed April 27, 1928. Serial No. 26,475. Term of patent 14 years.

To all whom it may concern:

Be it known that I, JONES T. TEMPLETON, a citizen of the United States, residing at St. Louis, Missouri, have invented a new, original, and ornamental Design for Heating Stoves, of which the following is a specification, reference being had to the accompanying drawing, forming part thereof.

Figure 1 is a front elevational view of the stove with outer doors closed, and

Figure 2 is a front elevational view thereof with the outer doors open.

I claim:

The ornamental design for a heating stove, as shown.

JONES T. TEMPLETON.
